J. F. LINDBERG

ELECTRIC SWITCH

Filed June 19, 1922

UNITED STATES PATENT OFFICE.

JOHN F. LINDBERG, OF CHICAGO, ILLINOIS, ASSIGNOR TO RELIANCE DIE AND STAMPING COMPANY, OF CHICAGO, ILLINOIS, A CORPORATION OF ILLINOIS.

ELECTRIC SWITCH.

Application filed June 19, 1922. Serial No. 569,347.

To all whom it may concern:

Be it known that I, JOHN F. LINDBERG, citizen of the United States, residing at Chicago, in the county of Cook and State of Illinois, have invented a certain new and useful Improvement in Electric Switches, of which the following is a full, clear, concise, and exact description.

The invention, broadly speaking, resides in a switch through which a circuit is closed, this switch including two engaging complementary contacts and a telephone receiver or other translating device having two terminals engageable with the aforesaid contacts, one of these contacts being operable by the terminal engaging it to separate this contact from the contact complementary thereto.

In embodying my invention in a telephone receiving station employing a plurality of telephones I provide as many such switches as there are telephones through which the telephone circuit is closed. The contacts of the switches are in series in the receiving circuit and serve to establish the circuit whether one or any number of telephones are plugged in.

Where an installation includes two such switches, for example, the two outermost ones of the four switch contacts are preferably in the nature of spring clips adapted to receive the telephone terminal plugs and the remaining switch contacts are operable by the telephone terminal plugs, being in the form of spring arms that are electrically connected by being integral parts of a U-shaped spring member. Bars are adjacent and spaced apart from the sides of such spring member distances less than the thickness of the telephone terminals whereby when the telephone terminals are received between the bars and the sides of the spring members such spring member sides are moved to separate them from their complementary contacts, the electrical connections between the complementary contacts being replaced by the telephone instruments.

The switch of my invention is of particular service when employed in connection with radio telephony, as will be apparent to those skilled in the art.

The invention will be more fully explained by reference to the accompanying drawing in which Fig. 1 is a plan view, partially broken away, of a switch con-

struction made in accordance with the preferred embodiment of the invention; Fig. 2 is a sectional view on line 2—2 of Fig. 1; Fig. 3 is a sectional view on line 3—3 of Fig. 2; Fig. 4 is a perspective view illustrating a U-shaped spring member, parts complementary thereto, and telephone terminal plugs engaging two of the complementary contacts, one of these terminals effecting the separation of these contacts, the other two complementary contacts being illustrated in engagement as no telephone terminals are shown as being connected therewith; and Fig. 5 is a diagrammatic illustration of the circuit arrangement involved.

Like parts are indicated by similar characters of reference throughout the different figures.

The telephone receiving circuit, such as the plate circuit of a radio outfit, has its sides 1 and 2 respectively terminating in terminals 3 and 4. U-shaped spring members 5, 6, 7 and 8 are interposed between these two terminals. The sides or arms 9, 10; 11, 12; 13, 14; 15 and 16 are switch contacts. These contacts respectively have as their complementary contacts the spring clips 17, 18, 19, 20, 21, 22, 23 and 24. The spring clips 17 and 24 are respectively connected with the circuit terminals 3 and 4. The spring clips 18 and 19 are electrically connected preferably by being formed out of the same piece of strip metal with the plate 25 that connects the same. Similarly, the plate 26 electrically connects the spring clips 20 and 21 and the plate 27 electrically connects the spring clips 22 and 23. The U-shaped spring members are interposed between adjacent clips that are not directly connected. Bars 28 are adjacent the sides of the U-shaped members and are spaced apart therefrom distances that are less than the thickness of the telephone terminals 29 and 30 so that when the telephone is inserted between either side of a U-shaped spring member and an adjacent bar 28, such side will be flexed to be separated from its complementary contact which receives the other telephone terminal. A telephone 31 having the terminals 29 and 30 thus establishes connection between the complementary contacts whose engagement is broken by the action of one of the telephone terminals.

I have illustrated two telephones as being looped into the circuit by means of the

switch of my invention, similar parts of these telephones being given similar characters of reference in the drawing.

It will be obvious, from an inspection of 5 the drawing, that the switch illustrated is adapted to include eight telephones in series in the telephone circuit.

While I have herein shown and particularly described the preferred embodiment of 10 my invention I do not wish to be limited to the precise details of construction shown as changes may readily be made without departing from the spirit of my invention, but having thus described my invention I 15 claim as new and desire to secure by Letters Patent the following:—

1. The combination of two switches, each switch including two engaging complementary contacts, the contacts of these 20 switches being in series, one of the contacts of each switch being operable by a circuit terminal engaging it to separate this contact from the contact complementary thereto, the two outermost ones of the four 25 switch contacts of the series being formed

to receive circuit terminals and the remaining switch contacts forming parts of a U-shaped spring member whose sides constitute these remaining contacts which are operable by the terminals. 30

2. The combination of two switches, each switch including two engaging complementary contacts, the contacts of these switches being in series, one of the contacts of each switch being operable by a circuit 35 terminal engaging it to separate this contact from the contact complementary thereto, the two outermost ones of the four switch contacts of the series being formed to receive circuit terminals and the remaining switch contacts forming parts of a U-shaped spring member whose sides constitute these remaining contacts; and bars adjacent and spaced apart from the sides of said spring member distances less than the thickness of the 40 terminals and between which and said U-member sides the terminals are receivable. 45

In witness whereof, I hereunto subscribe my name this 26th day of May A. D. 1922.

JOHN F. LINDBERG.
